UNITED STATES PATENT OFFICE

2,550,674

SUPPORTING COLUMN

John C. Curtis, Claremont, N. H., assignor to Joy
Manufacturing Company, a corporation of
Pennsylvania

Application April 21, 1944, Serial No. 532,173

19 Claims. (Cl. 254—93)

1

My invention relates to supporting columns, and more particularly to means for delivering liquid under pressure to an extensible supporting column of the hydraulically actuated type, and to the structural features of such a column.

In setting up a supporting column it is desirable that the operator be free to guide the abutment engaging members of the column while the latter is being extended by fluid delivered to it under pressure. After the abutment surfaces have been engaged and the column is supported without the aid of the operator, the operator may then do whatever is necessary to increase the abutment engaging pressure for holding the column firmly in the desired position. To effect the extending of the column into engagement with the abutment surfaces there may be provided a motor actuated pumping means or means for subjecting a body of liquid to pressure for forcing the latter to pistons which operate to extend the column. If the pressure at which the liquid is delivered to the pistons is not sufficient to hold the column in the desired position when the latter is subjected to the loads to be placed upon it, then some suitable manually actuated means may be provided for increasing the abutment engaging pressure. When the column is held extended only by the liquid delivered to it, it will be appreciated that any leakage of liquid from the column would permit the latter to collapse unless additional liquid was supplied. By maintaining a continuous connection between the motor actuated pumping means and its supply of operating fluid, the pumping means will operate and deliver liquid to the column until the latter can extend no further under the discharge pressure of the pumping means. The pumping means will then stall, but, as soon as liquid leaks from the column, the pumping means will automatically start again and pump liquid to the column until the maximum abutment engaging pressure is again reached. If the column is forced to its fully extended position only by the subjection of a body of liquid to a pressure, then the continuous subjection of the liquid body to pressure will cause liquid to be forced into the column to make up for leakage.

An object of my invention is to provide an improved supporting column. Another object of my invention is to provide an improved extensible supporting column of the fluid actuated type having improved means for delivering fluid under pressure to the column. Still another object of my invention is to provide improved means for delivering fluid under pressure to a fluid actuated

2

device. A further object of my invention is to provide an improved hydraulic column having improved means for automatically preventing collapse thereof due to leakage. Yet another object of my invention is to provide an improved fluid actuated pump. These and other objects of the invention will appear more fully in the following description.

In the accompanying drawings there are shown for purposes of illustration one form and two modifications which the invention may assume in practice.

In these drawings:

Fig. 1 is a front elevational view of an illustrative embodiment of my improved supporting column.

Fig. 2 is a view in longitudinal vertical section taken through the supporting column shown in Fig. 1.

Fig. 3 is an enlarged vertical sectional view showing a portion of the supporting column and improved means for pumping liquid from a liquid storage chamber to passages leading to fluid actuated pistons of the column, the view being taken on the plane of the line 3—3 of Fig. 1.

Fig. 4 is an enlarged view taken on the plane of the line 4—4 of Fig. 1 showing a portion of the supporting column in section and the remainder in plan.

Fig. 5 is a fragmentary sectional view taken on the plane of the line 5—5 of Fig. 4 and showing valve means for controlling the venting of fluid from the fluid actuated pistons of the column to the storage chamber.

Fig. 6 is a front elevational view showing a portion of a modified form of the invention.

Fig. 7 is an enlarged vertical sectional view taken on the plane of the line 7—7 of Fig. 6.

Fig. 8 is a vertical sectional view showing a modification of the fluid actuated pumping means of the form of the invention shown in Figs. 1 to 5.

In the illustrative embodiment of the invention shown in Figs. 1 to 5, inclusive, the improved supporting column is generally designated 1 and comprises a body portion 2 having laterally spaced bores 3 and 4 opening through its lower end, and a bore 5 located between the bores 3 and 4 and opening through its upper end. Fitting tightly within the bore 5 is a tubular shaped column member 7 carrying, at its upper end, an abutment engaging member 8 and cooperating, at its lower end, with a reduced bore 10 opening into the bore 5 to form a chamber space 12 for containing a body of liquid, such as oil. Reciprocable within the bores 3 and 4, respectively, are

pistons 14 and 15 carrying piston rods 16 and 17 which extend through bushings 18 attached, as by bolts 19, to the body portion 2, and the piston rods have fixed to their lower ends abutment engaging members 20 and 21.

Attached to the side of the body portion 2, as by bolts 23, is a cylinder block 24 having stepped coaxial bores 25 and 26 communicating with each other at their adjacent ends. Reciprocable within the bores 25 and 26 is a piston 28 having an enlarged head portion 29 fitting the bore 25 and a reduced head portion 30 fitting the bore 26. A passage 31 extends through the body portion 2 of the column and the cylinder block 24 to connect the chamber space 12 in communication with the lower end of the bore 26, and a spring pressed ball valve 33 opens to permit liquid to flow through the passage 31 toward the bore 26 and closes to prevent flow in the opposite direction. A passage 34 opens into the bore 26 at a point between the ends of the latter and communicates with the passage 31 at a point between the valve 33 and the chamber 12. Formed in the reduced head portion 30 of the piston 28 is a passage 35 opening through the lower end of the head portion 30 and opening through the side of the latter at a point to communicate with the passage 34 just before the piston 28 reaches the lower end of its stroke. The lower end of the bore 26 is connected under the control of a spring pressed ball valve 31 with a passage 38 which communicates with branch passages 39 and 40 opening, respectively, into the upper ends of the bores 3 and 4. It will be seen that when the position 28 is caused to reciprocate, the head portion 30 will operate to pump liquid from the chamber 12 to the bores 3 and 4. As soon as the bore 26 is connected to the chamber 12 through the passages 34 and 35 the pumping stroke terminates and the pressure beneath the piston drops permitting the latter to be moved more easily to the lower end of its stroke.

The upper end of the bore 25 is closed by a cylinder head 42, and a spring 43 acting between the lower side of the piston head portion 29 and the cylinder block 24 at the lower end of the bore 25 normally holds the piston 28 against this cylinder head. The space at the lower end of the head portion 29 communicates continuously with the atmosphere through a vent port 44. Formed within the cylinder head is a valve chamber 45 containing a piston type distributing valve 46 for controlling the supply of pressure fluid through a passage 48 to the cylinder bore 25 and for controlling the venting of fluid from the bore 25 through a passage 50. The passage 48 opens into an enlarged portion 51 of the valve chamber at a point to be covered by one end of the valve 46 when the latter is in one of its limiting positions, and a fluid supply conduit 52 opens into the chamber portion 51 at such a point that fluid supplied to the chamber must flow around a flange 54 on the valve 46 in order to reach the passage 48. The end portion 55 of the valve adjacent the passage 48 is slightly reduced in cross section to present an annular area 56 which is somewhat larger than the area 57 at the opposite side of the flange 54. It will be seen that with the valve in its open position, as shown in Fig. 3, a flow of fluid through the chamber portion 51 toward the passage 48 will act on the flange 54 to urge the valve toward its closed position and, if the flow of fluid becomes great enough, the force acting on

the valve will be sufficient to move the latter to its closed position. With the valve closed, the pressures at opposite sides of the flange 54 become equal, and the pressure acting against the larger area 56 tends to move the valve to its open position against the pressure acting on the area 57. The exhaust passage 50 opens into a chamber space 59 surrounding a reduced portion 60 of the valve 46, and the space 59 is connected, when the valve is seated, past the outer end of the reduced portion 60 to an exhaust port 61 in the cylinder head. On the valve 46 at the inner end of the reduced portion 60 is an annular area 62 which is subjected to the pressures in the bore 25 for opposing opening movements of the valve by the pressure acting on the area 56. Opening through the wall of the cylinder bore 25 is an exhaust port 63 which is so located that it is uncovered by the side of the piston portion 29 shortly after the passage 35 has been connected in communication with the passage 34.

The operation of the mechanism so far described is as follows: After the column has been placed in the desired position, the operator connects the conduit 52 in communication with a pressure fluid supply, as by opening a suitable valve not shown. If the valve 46 should be in its closed position, the fluid pressure builds up in the chamber portion 51 and acts against the valve area 56 to move the valve to its open position for supplying fluid to the bore 25 through the passage 48 and for cutting off the exhaust of fluid through the passage 50. Until the valve 46 opens, the area 62 is subjected only to atmospheric pressure and but little resistance is offered to the opening movement of the valve. As soon as the valve opens, the end portion 55, as well as the area 56, is subjected to the pressure in the bore 25, and the valve is held open even though the pressure in the bore acts on the area 62. The pressure fluid acts in the bore 25 against the top of the piston 28 and forces the latter downwardly against the action of the spring 43. Just before the piston reaches the lower end of its stroke, the bore 26 is connected through the passages 35 and 34 to the chamber 12, reducing the pressure which opposes the downward movement of the piston. The pressure in the bore 25 then forces the piston downwardly until the exhaust port 63 is uncovered and the bore 25 is freely vented to atmosphere. The reduction of the pressure in the bore 25 results in a rush of fluid through the valve chamber portion 51, and the action of this fluid on the valve flange 54 causes the valve 46 to be moved to a position covering the passage 48 and opening the exhaust passage 50. The piston 28 is then moved upwardly by the spring 43 as the pressure fluid escapes from the bore 25 through the exhaust passage. The escaping pressure fluid acts on the area 62 holding the valve closed against the force of the line pressure acting on the area 56. When the piston reaches its uppermost position, the pressure acting on the area 62 reduces rapidly and the valve 46 is unseated by the pressure acting on the area 56 to supply pressure fluid again to the bore 25. The reciprocation of the piston 28 causes liquid to be pumped from the chamber 12 through the passage 31, past the ball valve 33, through the bore 26, past the ball valve 37, through the passage 38 and the passages 39 and 40 to the bores 3 and 4 where it acts on the pistons 14 and 15 and effects an extension of the column until the abutment engaging members 8,

20 and 21 are firmly in engagement with abutments. The supply of pressure fluid through the conduit 52 is maintained while the column is in use, so that the pump will automatically introduce more fluid into the cylinders 3, 4, whenever there is any leakage such as to reduce the pressure therein.

When it is desired to lower the column, the supply of fluid through the conduit 52 is interrupted and a valve 65, as shown in Fig. 5, is manually adjusted to connect a passage 66, leading from the passage 38, in communication with a passage 67 opening into the chamber 12.

In Figs. 6 and 7 there is shown a modification of the invention in which a manually operated pump, generally designated 70, is provided for pumping liquid from the chamber 12 through the passages 31 and 38 to the bores 3 and 4. The pump 70 comprises a cylinder member 71 fitting within a bore 72 in a cylinder block 73 attached to the side of the body portion 2 of the column 1 and having a bore 74 containing a piston 75. The passages 31 and 38 communicate with the bore 74 under the control of the spring pressed ball valves 33 and 37, respectively. The upper end of the piston 75 is pivotally connected at 76 to an operating lever 77, and the operating lever is pivotally connected, at a point spaced longitudinally of the latter from the point 76, to one end of a link 78 which is pivotally connected at its other end to a collar 80 clamped, as shown in Fig. 7, between a flange 81 on the cylinder member 71 and a collar 82 threaded on the cylinder member.

In order to obtain a rapid extension of the column, there is provided a conduit 83 opening into the chamber 12 above the surface of the liquid therein and adapted to be connected by a manually operated valve 84 to a pressure fluid supply. In setting up the column, the valve 84 is opened to supply pressure fluid to the chamber 12 for forcing liquid from the latter through the passages 31 and 38 to the bores 3 and 4. After the abutments have been engaged by the members 8, 20 and 21, the valve 84 is closed and the pump lever 77 is operated to actuate the piston 75 for forcing a little more liquid to the bores 3 and 4 and effecting a very powerful engagement of the abutments.

Fig. 8 shows a fluid actuated pump similar to that of Fig. 3, but in this case the piston 28 is provided with a portion 85 between the head portions 29 and 30 and fitting a bore 86 which is somewhat larger than the bore 26 but is smaller than the bore 25. A conduit 88 supplies pressure fluid to a passage 89 opening into the lower end of the bore 86, and this pressure fluid acts on an annular area 87 on the piston portion 85 for yieldingly urging the piston toward the cylinder head 42. The distributing valve 46' controls the flow of pressure fluid relative to the bore 25 for effecting, in the same manner as that described in the first form of the invention, the reciprocation of piston 28. In this case the distributing valve has a reduced portion 90 which is somewhat smaller than the opening 91 connecting the space 59 with the exhaust port 61. At the outer end of the portion 90 is an enlarged portion 92 which moves into the opening 91 with just enough clearance to provide a restricted opening to exhaust when the valve is in its closed position. By appropriately selecting the area of the portion 92 relative to the area of the face 93 on the body of the valve, a substantial holding force for keeping the valve seated can be provided, while

at the same time a clean-cut opening movement of the valve may be insured because as the valve opens an increased venting passage area is provided at its left hand end as the portion 92 moves out of the opening 91 and the smaller portion 90 extends through the opening.

As a result of my invention, it will be noted that there is provided an improved fluid actuated supporting column having improved means for delivering to the column, a fluid under pressure. While the column shown herein is extended by an incompressible fluid, it will be understood that the fluid delivery means associated with the column is adapted for use in the delivery of a gaseous fluid. It will be noted that by reason of the provision of the fluid delivery means, the operator is free to support the column in the desired position as it is extended into engagement with extraneous abutments. With the pressure generating means operating automatically to compensate for any pressure drop in the supporting column, it will be seen that the pressure will be maintained and the column will not collapse because of the leakage of fluid therefrom. A rapid extension of the column is obtained by the subjection of the body of liquid to a continuous pressure, and, if further extension is needed under increased pressure, such extension may be quickly obtained by manually actuated means. Because of the provision of a plurality of abutment engaging members at one end of the column, these members being actuated by separate pistons to which fluid is delivered from a common source, there will be an automatic adjustment of the members to compensate for unevenness in the abutment surface.

While there are in this application specifically described one form and two modifications which the invention may assume in practice, it will be understood that these are shown for purposes of illustration and that the invention may be further modified and embodied in various other forms without departing from its spirit or the scope of the appended claims.

What I claim as new and desire to secure by Letters Patent is:

1. In a supporting column, in combination, a body member having parallel, offset bores opening through opposite ends thereof, a tubular shaped member fixed at one end within one of said bores and having an abutment engaging member at its outer end, a piston reciprocable within another of said bores and carrying a piston rod to the outer end of which an abutment engaging member is attached, said tubular member cooperating with said body member to form a liquid storage space, and means for delivering liquid under pressure from said storage space to said piston for effecting relative movement of said abutment engaging members into engagement with extraneous abutments.

2. In a supporting column, in combination, a body member having a centrally located bore opening through one end thereof, a tubular shaped member fixed at one end within said bore and projecting from said body member, an abutment engaging member attached to the outer end of said tubular member, a plurality of bores opening through the opposite end of said body member and arranged in parallelism with said centrally located bore and spaced equi-distantly from the latter at the opposite sides of said body member, pistons reciprocable within said plurality of bores and each carrying a piston rod to the outer end of which an abutment engaging

member is attached, said tubular member co-operating with said body member to form a liquid storage space, and means for delivering liquid under pressure from said liquid storage space to said pistons for effecting relative movement of said abutment engaging members into engagement with extraneous abutments.

3. In a supporting column, in combination, a body member having a centrally located bore opening through one end thereof, a tubular shaped member fixed at one end within said bore and projecting from said body member, an abutment engaging member attached to the outer end of said tubular member, a pair of bores opening through the opposite end of said body member at points spaced equidistantly from opposite sides of the axis of said first mentioned bore in parallelism with the latter, pistons reciprocable within said pair of bores and each carrying a piston rod to the outer end of which an abutment engaging member is attached, said tubular member cooperating with said body member to form a liquid storage space, and means for delivering liquid under pressure from said liquid storage space to said pistons for effecting relative movement of said abutment engaging members into engagement with extraneous abutments, said last mentioned means including common passage means communicating with said pair of bores.

4. An extensible column comprising, in combination, a member providing a bore, a piston reciprocable in said bore for varying the length of said column, means for delivering fluid under pressure to said piston for effecting an extension of the column, said last mentioned means including stepped cylinder bores opening into each other, a piston having portions reciprocable in each of said cylinder bores, one of said piston portions acting as a pump piston and the other acting as a motor piston, valve means for controlling the supply of operating fluid to said motor piston, means for yieldingly opposing movement of said motor piston by the operating fluid supplied thereto, means for venting fluid from said motor piston at the end of the working stroke of the latter, fluid supply and discharge passages for conducting fluid relative to said pump piston, inlet and discharge valves for controlling the flow of fluid through said supply and discharge passages, and passage means for connecting the working end of said pump piston to said fluid supply passage at the supply side of said inlet valve shortly before the end of the pumping stroke is reached.

5. An extensible column comprising, in combination, a member providing a bore, a piston reciprocable in said bore for varying the length of said column, means for delivering fluid under pressure to said piston for effecting an extension of the column, said last mentioned means including stepped cylinder bores opening into each other, a piston having portions reciprocable in each of said cylinder bores, one of said piston portions acting as a pump piston and the other acting as a motor piston, valve means for controlling the supply of operating fluid to said motor piston, means for yieldingly opposing movement of said motor piston by the operating fluid supplied thereto, means for venting fluid from said motor piston at the end of the working stroke of the latter, fluid supply and discharge passages for conducting fluid relative to said pump piston, inlet and discharge valves for controlling the flow of fluid through said supply and

discharge passages, and means for venting the space at the working end of said pump piston shortly before operating fluid is vented from said motor piston.

6. In a supporting column, in combination, a body member having bores opening through opposite ends thereof, a tubular shaped member fixed within one of said bores and having an abutment engaging member at its outer end, a piston reciprocable within another of said bores and carrying a piston rod to the outer end of which an abutment engaging member is attached, said tubular member cooperating with said body member to form a liquid storage space, means for delivering liquid under pressure from said storage space to said piston for effecting relative movement of said abutment engaging members into engagement with extraneous abutments, said last mentioned means including a cylinder bore containing a reciprocable piston, valve controlled passage means connecting said cylinder bore in communication with said liquid storage space and with said first mentioned piston, means for effecting reciprocation of said last mentioned piston, and means for subjecting the surface of the liquid in said storage space to the action of a pressure fluid.

7. A pump mechanism comprising, in combination, means providing a cylinder bore, a piston reciprocable in said cylinder bore, means for yieldingly urging said piston toward one end of said bore, means for supplying operating fluid to one end of said piston for forcing the latter through working strokes against the action of said yielding means, means for venting operating fluid from said piston at the end of its working strokes, valve controlled supply and discharge passages for conducting fluid to be pumped relative to an area at the opposite end of said opposite end of said piston, and means for venting fluid from said piston area shortly before the end of the working stroke of said piston is reached.

8. A pump mechanism comprising, in combination, means providing stepped cylinder bores opening into each other, a piston having portions reciprocable in each of said bores, means including a valve for controlling the supply of operating fluid to one of said piston portions, means for yieldingly opposing movement of said piston by the operating fluid supplied thereto, means for venting operating fluid from said piston after a predetermined movement of the latter, fluid supply and discharge passages for conducting fluid to be pumped relative to the other of said piston portions, inlet and discharge valves for controlling the flow of fluid through said supply and discharge passages, and means for venting fluid from the other of said piston portions shortly before operating fluid is vented from the first of said piston portions.

9. A pump mechanism comprising, in combination, means providing stepped cylinder bores opening into each other, a piston having portions reciprocable in each of said bores, means including a valve for controlling the supply of operating fluid to one of said piston portions, means for yieldingly opposing movement of said piston by the operating fluid supplied thereto, means for venting operating fluid from said piston after a predetermined movement of the latter, fluid supply and discharge passages for conducting fluid to be pumped relative to the other of said piston portions, inlet and discharge valves for controlling the flow of fluid through said supply and discharge passages, means for venting fluid from the

other of said piston portions shortly before operating fluid is vented from the first of said piston portions, said last mentioned means including a vent passage opening into the bore containing the other of said piston portions, and passage means extending through the other of said piston portions and communicating with said vent passage shortly before the end of the pumping stroke of said piston.

10. A pump mechanism comprising, in combination, means providing stepped cylinder bores opening into each other, a piston having portions reciprocable in each of said bores, means including a valve for controlling the supply of operating fluid to the larger one of said piston portions, means for yieldingly opposing movement of said piston by the operating fluid supplied thereto, means for venting operating fluid from said larger piston portion after a predetermined movement of the latter, fluid supply and discharge passages for conducting fluid to be pumped relative to the smaller of said piston portions, inlet and discharge valves for controlling the flow of fluid through said supply and discharge passages, and means for venting fluid from the smaller of said piston portions shortly before operating fluid is vented from the larger one of said piston portions.

11. A pump mechanism comprising, in combination, means providing stepped cylinder bores opening into each other, a piston having portions reciprocable in each of said bores, means including a valve for controlling the supply of operating fluid to the larger one of said piston portions, means for yieldingly opposing movement of said piston by the operating fluid supplied thereto, means for venting operating fluid from said larger piston portion after a predetermined movement of the latter, fluid supply and discharge passages for conducting fluid to be pumped relative to the smaller of said piston portions, inlet and discharge valves for controlling the flow of fluid through said supply and discharge passages, means for venting fluid from the smaller of said piston portions shortly before operating fluid is vented from the larger one of said piston portions, said last mentioned venting means including a vent passage opening into the smaller of said cylinder bores between the ends of the latter, and passage means in said smaller piston portion adapted to communicate with said vent passage before the end of the working stroke of said piston is reached.

12. A pump mechanism comprising, in combination, means providing three coaxial cylinder bores decreasing progressively in diameter, the middle one of said bores opening into the other two, a piston having portions reciprocable in each of said bores, means including a valve for controlling the supply of operating fluid to the larger one of said bores, means for supplying pressure fluid to the middle one of said piston portions for opposing movement of said piston by said operating fluid, means for venting operating fluid from said larger piston portion after a predetermined movement of the latter in a working direction, fluid supply and discharge passages for conducting fluid to be pumped relative to the smaller one of said piston portions, inlet and discharge valves for controlling the flow of fluid through said supply and discharge passages, and means for venting fluid from the smaller one of said piston portions shortly before operating fluid is vented from the larger one of said piston portions.

13. A pump mechanism comprising, in combination, means providing a cylinder bore, a piston reciprocable in said cylinder bore, valve means for controlling the supply of operating fluid to and the exhaust of fluid from said cylinder bore at one end of said piston, said valve means movable to its exhaust effecting position on the venting of operating fluid from said bore, means for venting operating fluid from said bore at the end of the working stroke of said piston, means for yieldingly opposing movement of said piston by the operating fluid, valve controlled supply and discharge passages for conducting fluid to be pumped relative to an area at the opposite end of said piston, and means for venting fluid from said piston area shortly before the end of the working stroke of said piston is reached.

14. A pump mechanism comprising, in combination, means providing stepped cylinder bores opening into each other, a piston having portions reciprocable in each of said bores, valve means for controlling the supply of operating fluid to and the exhaust of fluid from one of said bores, said valve means movable to its exhaust effecting position on the venting of operating fluid from said bore, means for venting operating fluid from said bore after a predetermined movement of said piston in its working stroke, means supplying pressure fluid to another of said bores for opposing movement of said piston by the operating fluid supplied thereto, fluid supply and discharge passages for conducting fluid to be pumped relative to another of said bores, inlet and discharge valves for controlling the flow of fluid through said supply and discharge passages, and means for venting fluid from the last mentioned one of said bores shortly before operating fluid is vented from the first mentioned one of said bores.

15. In a supporting column, in combination, a lower frame, an elongated upright support secured to said frame midway between the sides of the latter and having a roof engaging member at its upper end, a pair of extensible hydraulic cylinder and piston devices secured to said frame and arranged in parallelism with said elongated support and spaced equi-distantly therefrom at opposite sides of said frame, said cylinder and piston devices having foot pieces thereon below said frame and engageable with the floor, a liquid pump carried by said frame intermediate said devices and in adjacency to the lower end of said support, and valve controlled passage means in said frame between the cylinders of said devices and having connection with said pump between said cylinders for supplying liquid under pressure concurrently to said devices to extend the latter to bring said foot pieces firmly into engagement with the floor even when the latter is uneven.

16. In a supporting column, in combination, a lower frame, an elongated upright support secured to said frame midway between the sides of the latter and having a roof engaging member at its upper end, a pair of extensible hydraulic cylinder and piston devices secured to said frame and arranged in parallelism with said elongated support and spaced equi-distantly therefrom at opposite sides of said frame with the upper ends of said devices extending upwardly relative to the lower end of said support and with the lower ends of said devices near the bottom of said frame, said cylinder and piston devices having foot pieces thereon below said frame and engageable with the floor, a liquid pump carried by

said frame intermediate said devices and in adjacency to the lower end of said support, and valve controlled passage means in said frame between the cylinders of said devices and having connections with said pump between said cylinders for supplying liquid under pressure concurrently to said devices to extend the latter to bring said foot pieces firmly into engagement with the floor even when the latter is uneven.

17. In a hydraulic mine column, a pair of parallel extensible cylinder and piston devices respectively having floor engaging abutments, a cross connecting frame extending between and secured to said devices, a column element supported by said cross frame midway between said parallel devices and extending vertically above said cross frame, said column element having a roof engaging abutment, a source of liquid under pressure on said cross frame, passages in said cross frame for connecting said liquid source to the cylinders of said devices, and means on said cross frame for effecting liquid flow from said source through said passages to the cylinders of said devices whereby the pistons of said devices may be concurrently subjected to the action of hydraulic pressure to extend said devices to bring about, with the column element vertical, firm engagement of said floor engaging abutments with the floor, whether the latter is level, uneven or sloping, and also firm engagement of said roof engaging abutment with the roof, whereby said column may be fixed in vertical position, and said liquid flow effecting means embodying means operative to effect trapping of liquid in the cylinders of said devices to hold the latter firmly in adjusted position thereby to secure the column in place between the roof and floor.

18. In a hydraulic mine column, a centrally located vertical column element having a roof engaging abutment and a base providing a cross frame, a pair of extensible cylinder and piston devices arranged in parallelism on said base at the opposite sides of said cross frame and spaced equidistantly from said centrally located column element, said devices respectively having floor engaging abutments, a source of liquid under pressure on said base, passages in said cross frame for connecting said liquid source to the cylinders of said devices, and means for effecting flow of liquid under pressure from said source through said passages to the cylinders of said devices for concurrently subjecting the pistons of said devices to the action of hydraulic pressure to extend said devices to bring about, with the column element vertical, firm engagement of said floor engaging abutments with the floor, whether the latter is level, uneven or sloping, and also firm engagement of said roof engaging abutment with the roof, whereby said column may be fixed in vertical position, and said liquid flow effecting means embodying means operative to effect trapping of liquid in the cylinders of said devices.

to hold the latter firmly in adjusted position thereby to secure the column in place between the roof and floor.

19. In an extensible hydraulic supporting column, a bottom frame having a transverse portion, a vertical column element secured centrally to said transverse frame portion and extending upwardly and provided at its upper end with a roof engaging abutment, a pair of cylinder and piston devices carried at the sides of said transverse frame portion and arranged in parallel relation and spaced equidistantly from said column element, said devices having floor engaging abutments at their lower ends, a liquid reservoir carried by said bottom frame, a pump on said bottom frame, passages in said transverse frame portion for connecting said pump to said reservoir and to the cylinders of said devices, and means for effecting flow of liquid from said pump through said passages to the cylinders of said devices concurrently to extend the latter to bring about, with the column element vertical, firm engagement of said floor engaging abutments with the floor, whether the latter is level, uneven or sloping, and also firm engagement of said roof engaging abutment with the roof, whereby said column may be fixed in vertical position, and said flow effecting means being operative to effect trapping of liquid in the cylinders to hold firmly said devices in adjusted position thereby to secure the column in place between the roof and floor.
